UNITED STATES PATENT OFFICE.

ELMER B. KALEY, OF INDIANAPOLIS, INDIANA, ASSIGNOR OF ONE-HALF TO WILLIAM H. THOMAS, OF INDIANAPOLIS, INDIANA.

CARBURETER.

No. 921,410.

Specification of Letters Patent.

Patented May 11, 1909.

Application filed July 27, 1908. Serial No. 445,455.

To all whom it may concern:

Be it known that I, ELMER B. KALEY, a citizen of the United States, residing at Indianapolis, in the county of Marion and State of Indiana, have invented certain new and useful Improvements in Carbureters; and I do declare the following to be a full, clear, and exact description of the invention, reference being had to the accompanying drawings, and to the letters and figures of reference marked thereon, which form a part of this specification.

This invention relates to carbureters that are used in connection with explosive engines and especially such as are designed for use on automobiles, the invention having reference particularly to the apparatus for admitting and controlling air to be carbureted, and to apparatus for feeding the gasoline or similar hydro-carbon wherewith to produce the explosive mixture for the engines.

Objects of the invention are to provide an improved carbureter of the above mentioned character, which may be produced at reasonable expense, and adapted to be operated reliably, and with the highest efficiency under various conditions required, and be durable and economical in use; a further object being to provide an improved carbureter that will be adapted to be readily connected with engines at any required angle so as to be convenient in operation.

With the above mentioned and other objects in view, the invention consists in a carbureter having novel features of construction generally and particularly with respect to the carbureting tube, the carbureter including an improved combined admission and regulating valve for the air; and the invention consists further in the parts and combinations and arrangements of parts, as hereinafter particularly described and defined in the accompanying claims.

Referring to the drawings, Figure 1 is a top plan of the improved carbureter; Fig. 2, a vertical longitudinal sectional view on the line A—A in Fig. 1; Fig. 3, a vertical transverse sectional view on the line B—B in Fig. 1; Fig. 4, a fragmentary transverse sectional view as at the plane of the line C—C in Fig. 1; Fig. 5, a transverse sectional view on the line D in Fig. 1; Fig. 6, a fragmentary transverse sectional view on the line E in Fig. 1; Fig. 7, a fragmentary

horizontal sectional view in the plane of the line F—F in Fig. 4; and Fig. 8, a fragmentary transverse sectional view approximately on the line G—G in Fig. 7 omitting parts shown therein. 60

Similar reference characters in the various figures of the drawings indicate like elements or features of construction referred to herein.

A practical embodiment of the invention 65 comprises a reservoir 1 having a valve body 2 formed at the bottom thereof in which is a valve seat 3, the valve body being provided with a coupling-nut 4 connecting a feed pipe 5 to the valve body, the pipe 5 being 70 adapted to be connected to any source of supply whereby to supply the reservoir as needed with gasoline or the like. A feed valve 6 is arranged in the valve body to operate in connection with the valve seat 3 75 and it is provided with a valve stem 7 that extends up through the reservoir, the latter being provided with a cover 8 in which is an aperture 9 through which the valve stem extends loosely, the stem being guided in the 80 aperture in which there is sufficient space to permit air to pass through.

The top of the valve stem is provided with a knob 10 for manually operating the valve 6, but normally in operation the valve may be controlled by a float 11 preferably composed of cork and suitably secured to the valve stem 8, preferably by means of a collar 12 secured to the float and provided with a set screw 13 engaging the valve stem. 90 When the reservoir is empty the valve will open by force of gravity, and when sufficient liquid passes into the reservoir to raise the float it will close the valve. The reservoir has a projection 14 on the exterior thereof 95 that is preferably cast integrally and connects the wall of a carbureting tube 15 with the wall of the reservoir, the carbureting tube being preferably cast integrally with the projection. The carbureting tube, extends horizontally with respect to the vertical reservoir and has an enlarged open end forming a regulator valve case 16 that has an external flange 17 and preferably an internal flange 17' on its end. An annular 100 plate 18 is secured to the flange 17 removably by screw-bolts 19, the plate extending inward beyond the inner edge of the flange 17' and forming a valve-seat 18' at the inner side thereof. A guide-bar 20 is sup- 110

ported by the plate 18, being preferably formed integrally therewith, and it has a guide opening 20' therein. The plate 18 supports also a yoke 21 which is preferably formed integrally with the plate and extends over the guide opening 20' at a suitable distance outwardly therefrom. A guide-rod 22 is screwed into the yoke 21 and extends through the guide opening 20' into the bowl, and it has a lock-nut 23 thereon normally engaging the front or outer side of the yoke. A sleeve 24 is provided and arranged movably on the guide-rod 22, so as to move in the guide opening 20', the sleeve being a holder for a valve which is designed to admit air into the carbureting tube and to regulate the admission of the air. The valve comprises a disk 25 which is mounted on the sleeve and has a suitable number of apertures 26 therein, the disk being seated against a nut 27 that is screwed onto the sleeve, the valve comprising also a companion disk 28 having apertures 29 therein registering with the apertures 26, the disk 28 being placed on the sleeve against the disk 25 and secured thereto by a nut 27' screwed on to the sleeve 24, so that either or both nuts 27, 27' may be readjusted, in order that the valve disks may be readjusted along the sleeve and also when either nut is slackened either disk may be readjusted rotatively, so as to partially close the apertures therein more or less as may be desired. The inner end of the guide-rod 22 has a plate 30 connected thereto preferably so as to rotate thereon, and a coil-spring 31 is seated against the plate 30 and also against the disk 28, so as to normally hold the disk 25 against the seat 18', and the tension of the spring may be varied by adjusting the guide-rod 22 in the yoke 21. The plate 18 may be detached from the flange 17 in order to have access to the valve disks for readjusting them, although they may not require readjustment after having once been suitably adjusted to adapt the valve for the services required.

A valve-seat 32 is formed in the wall of the carbureting tube 15 near the valve case 16 and is provided with a regulating valve 33 that is mounted in a valve body 34 preferably formed integrally with the wall of the carbureting tube, the valve having an operating stem 35 screwed into the valve body, the latter being provided with a packing-nut 36 and connected by a duct 37 with the reservoir 1. The valve body 34 has a branch 38 that is in alignment with the duct 37 and normally closed by a cap 39, and when the cap is removed the duct may be readily cleared of any obstructions that may form therein; and by removing the valve stem 35, the passage from the duct to the carbureting tube may be readily cleared of obstructions.

65 The carbureting tube is provided with a

regulator that preferably comprises a rotative shaft 40 that is mounted in the wall of the carbureting tube, the wall being provided with a packing-box 41 on the exterior thereof through which the shaft extends, there being a packing-nut 42 on the packing-box, so that the shaft may be packed for producing friction sufficient to hold the shaft against turning when the apparatus is operating, the shaft being provided with an operating handle 43 on its outer end, and a disk 44 is secured to the shaft by a setscrew 45 or otherwise within the carbureting tube, so that the passage-way in the carbureting tube may be partially closed more or less as may be desired or required to supply the explosive engine with carbureted air or vapor.

In order to conveniently set the apparatus, the carbureting tube 15 has a flange 46 that is arranged at an oblique-angle thereto and an end piece 47 has a similar oblique-angle flange 48 engaging the flange 46, a coupling-nut 49 connecting the two flanges together adjustably, the end 47 having screw threads 50 by which it may be connected to the connecting pipe or directly to the explosive chamber or cylinder of the engine. It will be clear that if the nut 49 be slackened the end piece may be turned so as to extend at any desired angle with respect to the body of the carbureting tube.

In practical use the carbureting liquid will be conducted from the main supply tank through the pipe 5 and be fed automatically into the reservoir 1 by means of the valve 6 and the float 11, and in case the valve 6 sticks and fails to open at first it may be opened by manipulation of the knob 10 by hand, and when desired the valve may be held in closed position by means of the knob and the valve stem. When starting the engine the valve disk 40 will be suitably adjusted and sufficient air will at first be drawn in through the apertures 26 and 29 in the air regulating valve and the admission of the gasoline or other liquid will be controlled by the valve 33. As the engine increases in speed and sufficient suction is produced the valve disk 25 will be intermittently unseated, so that greater quantities of air will be admitted between the valve seat 18' and the disk 25, passing between the flange 17' and the disk 25 into the valve case 16 and thence into the carbureting tube, the air in its passage becoming carbureted by the liquid and causing the liquid to be atomized, the supply of the resultant gaseous fluid being governed partially by adjustments of the valve 44.

Having thus described the invention, what is claimed as new, is—

1. A carbureting tube having an enlarged end open to the atmosphere, an annular plate secured to the enlarged end and having a

valve-seat thereon facing inward, a yoke on the enlarged end, a guide-rod mounted in the yoke and having a bearing-plate thereon, an apertured valve guided by the guide-rod 5 to engage the valve-seat, a plate attached to the valve and adjustable thereon to partially close the apertures therein, and a coil-spring seated against the bearing-plate and acting to normally hold the valve on the 10 valve-seat.

2. A carbureter including a carbureting tube having an enlarged end open to the atmosphere, an annular plate secured to the enlarged end and having a valve-seat thereon, a guide-bar on the annular plate and having a guide-opening therein, a yoke on the annular plate opposite to the guide-bar, a guide-rod screwed into the yoke and extending through the guide-opening and into 20 the enlarged end, a sleeve movable on the guide-rod longitudinally of the guide-rod, a valve secured adjustably on the sleeve, a bearing-plate on the inner end portion of the guide-rod, and a spring seated against 25 the bearing-plate and acting to normally hold the valve on the valve-seat.

3. A carbureter including a carbureting tube having an enlarged end open to the atmosphere, an annular plate secured to the 30 enlarged end and having a valve-seat thereon facing inward, a yoke on the enlarged end, a guide-rod mounted in the yoke and having a bearing plate thereon, a sleeve movable on the guide-rod, two nuts screwed 35 onto the sleeve, a valve comprising two disks mounted on the sleeve between the nuts and

having registering apertures therein, and a spring engaging the bearing-plate and acting to normally hold the outer one of the valve disks to the valve-seat.

4. A carbureter comprising a reservoir, a valve at the bottom of the reservoir having an operating stem, a float in the reservoir secured to the stem, a carbureting tube connected to the reservoir and having an enlarged open end and an oblique-angled flange on the opposite end thereof, an end-piece having an oblique-angled flange thereon, a coupling nut connecting the two flanges together, an annular plate secured to the enlarged end and having a valve-seat thereon, a guide-bar on the annular plate and having a guide-opening therein, a yoke on the annular plate, a guide-rod screwed into the yoke and having a bearing-plate thereon, a 50 sleeve movable on the guide-rod and in the guide-opening, two nuts screwed onto the sleeve, a valve comprising two disks mounted on the sleeve between the nuts and having registering apertures therein, a spring 55 engaging the bearing-plate and one of the disks and normally holding the other disk of the valve on the valve-seat, and a regulating valve between the reservoir and the tube.

In testimony whereof, I affix my signature in presence of two witnesses, on the 17th day of July, 1908.

ELMER B. KALEY.
